Milton F. Williams,
BY *H. M. Paisted,*

ATTORNEY.

UNITED STATES PATENT OFFICE.

MILTON F. WILLIAMS, OF ST. LOUIS, MISSOURI, ASSIGNOR TO WILLIAMS PATENT CRUSHER AND PULVERIZER CO., OF ST. LOUIS, MISSOURI, A CORPORATION OF MISSOURI.

BREAKER-PLATE FOR GRINDERS.

1,274,126.

Specification of Letters Patent. Patented July 30, 1918.

Application filed February 12, 1918. Serial No. 216,681.

To all whom it may concern:

Be it known that I, MILTON F. WILLIAMS, a citizen of the United States, residing at St. Louis, State of Missouri, have invented 5 certain new and useful Improvements in Breaker-Plates for Grinders, of which the following is a specification.

This invention relates to certain new and useful improvements in breaker plates for 10 grinders, the object of which is to provide means to effect a preliminary breaking up of the feed, prior to finer reduction on the lower portion of the breaker plate. A further object is to facilitate changing the 15 operation of a mill such as shown in my Patent 758,288 dated April 26, 1904, by substituting the breaker plate that is the subject of the present application for the plain breaker plate that is shown in said patent. 20 The peculiarities of construction will be hereinafter described in the specification and particularly pointed out in the claim.

In the accompanying drawing on which like reference letters indicate corresponding parts:

Figure 1 represents a vertical cross section of a grinder embodying my improvement; and

Fig. 2, a separate perspective view of my 30 one-piece breaker plate.

The letter A designates any suitable housing or casing of a grinder, having a hopper B, the bottom C of which inclines downward substantially tangential to the path of hammers D, pivoted to disks E, keyed to a shaft F, mounted in suitable bearings (not shown) in said housing. An arcuate cage G, of bars or other suitable construction, co-operates 35 with said hammers in grinding the material till it is fine enough to pass through the cage, and extends preferably from the central horizontal plane around toward the hopper bottom C, where it meets a breaker plate H that is flush with and forms the 40 continuation of said bottom, and is substantially in alinement with both the hopper bottom and said cage.

This breaker plate is secured in its operative position by, for example, a wedge key I through a slot in a back lug J, and shims 50 K, or other means to allow adjustment of the working front of the breaker plate toward or away from the path of said hammers.

This working front is made up of two faces, L and M, preferably of diverging inclined planes, connected by an intermediate plane N, reversely inclined or otherwise formed so as to constitute a step, the edge n of which is farther away from the path of the hammers than is the lower face of 60 the breaker plate. Thus the higher face L is substantially a continuation of the hopper bottom but at lesser inclination to the horizontal, while the lower face M is steeper and substantially tangent to the arcuate cage. 65 This step therefore serves in conjunction with the hammers as a fulcrum or breaking edge for bark, oil cake, and other material, that thus suffers a preliminary breaking as it is fed into the hopper,—which preliminary breaking is prior to further reduction on said lower face of the breaker plate, 70 which reduction is finished on the cage abutting the lower face. This action is indicated in Fig. 1, where the feed is shown broken over the fulcrum edge by the hammers, and sliding down the lower face into closer proximity to the path of the hammers, till it is delivered upon the arcuate cage.

The upper breaking face is preferably 80 smooth to facilitate entrance of the feed, but the lower breaker face may be either smooth, or corrugated as indicated at m Fig. 2, or otherwise, depending on which style is best adapted to hold back and effect the second 85 reduction of the material being ground.

I claim:

A machine of the character described, comprising a suitable housing having a feed hopper with a slant bottom, an arcuate cage 90 and rotary hammers mounted in said housing, a breaker plate located between the end of said bottom and the adjacent end of said cage,—the front of said plate consisting of

a smooth upper face forming a continuation of said slant bottom and flush therewith to form a smooth passageway for the feed, a lower corrugated face to grind the material **6** in conjunction with said hammers and an intermediate step between said faces serving as a fulcrum for preliminary breaking of the feed by said hammers prior to second reduction on the lower face, before final re-

duction on said cage, substantially as de- **10** scribed.

In testimony whereof I have affixed my signature in the presence of two witnesses.

MILTON F. WILLIAMS.
